Inventor:

Hermann Wartenberg

By *J. Daniels, Jr.*
Attorney

UNITED STATES PATENT OFFICE.

HERMANN WARTENBERG, OF CHARLOTTENBURG, NEAR BERLIN, GERMANY.

EXPLOSION ENGINE.

Application filed October 18, 1922. Serial No. 595,307.

To all whom it may concern:

Be it known that I, HERMANN WARTENBERG, a citizen of the German Republic, residing at Charlottenburg, near Berlin, Germany, have invented certain new and useful Improvements in Explosion Engines, of which the following is a specification.

My invention relates to explosion engines or socalled internal combustion engines, and in particular to a device for keeping the cooling water required by such engine constantly at a certain temperature.

The object of my invention, therefore, is to provide a simple and efficient means for automatically regulating the temperature of the water supplied to the engine for cooling purposes.

With this object in view the invention consists of certain novel features of construction comprising mainly a spring-controlled valve in a casing adapted to be inserted in the cooling water conduit of an explosion engine, and a socalled thermostatic tube connected with said valve in a manner to control the passage through said casing in accordance with the fall and rise of the temperature of the water flowing through the said conduit.

Further objects and advantages of my invention will be set forth in the detailed description which now follows.

In the accompanying drawings; Figure 1 represents a vertical section through the casing containing the spring-controlled valve and the thermostatic regulating member; Figure 2 is a similar sectional view of a modification embodying means for setting and adjusting both the controlling spring and the thermostatic member; Figure 3 is a sectional view on an enlarged scale according to line A—B of Figure 2.

Referring to the embodiment shown in Fig. 1 *a* designates the casing with an inlet *b* and an outlet *c* adapted to be inserted in the cooling water conduit of the engine. A partition wall *d* is provided in the casing so that two separate rooms *e* and *f* are formed therein. A cock *g* is provided in the wall of the casing for emptying purposes.

The partition *d* is cut out to form a seat for a valve *h* which is loosely mounted on a fixed rod *i*, that is to say, so as to be displaceable thereon in an axial direction. The two threaded ends of the rod *i* are mounted

each in a spider or the like *k* and *l*, respectively, and nuts are employed for setting and fixing the rod therein as clearly shown in the drawing. The valve *h* is under the control of a spring *m*, constantly acting to press the same into its seat in the partition *d*.

A thermostatic tube *n* is mounted on the rod *i* in the following manner. The upper end of the tube carries a sleeve *o* and the lower end thereof carries a disk or ring *p*, both the sleeve and the ring being rigidly connected with the tube, which preferably has a circular shape. The ring *p* and the sleeve *o* loosely engage the rod *i*, but the sleeve *o* is set to cause the ring *p* to abut against the valve *h* which, as above stated, likewise is axially displaceable on the rod *i*. In the wall of the sleeve a small screw is provided for fixing the sleeve and the tube *n* in the set or adjusted position on the rod *i*.

From the above description it will be seen that the thermostatic tube *n* is intended to counteract the action of the spring *m* in order to lift the valve from its seat and to allow cooling liquid to pass through the outlet *c* to an amount depending upon the throw of the thermostatic tube *n*.

In the modification shown in Figures 2 and 3 the very same principle is embodied, that is to say, a valve is provided therein which is controlled by a thermostatic tube to keep the temperature of the cooling water to be supplied to the engine, at a certain height to ensure the best cooling effect in the engine.

In the embodiment illustrated in Figures 2 and 3 means are provided for setting or adjusting the thermostatic tube *n* and the controlling spring *m* of the valve from the outside of the casing. To this end a rod or shaft *q* is mounted in a suitable bearing *q'* integral with the casing *a* and a cam or arm *r* is firmly connected with the inner end of said shaft *q* so as to engage the flange *s* of a sleeve *t*. The latter is loosely mounted on the rod *i* and the valve controlling spring *m* is disposed on the rod *i* so as to abut with its one end against the valve *h* and with its other end against the said sleeve *t*.

The outer end of the shaft *q*, Figure 3, is shaped to form a collar *u* adapted to be embedded in a correspondingly shaped recess of the bearing *q'*. A disk *v* surround-

ing the projecting end of the shaft q is provided for the purpose of frictionally fixing the collar u within the said recess by means of screws w , after the spring m has been duly set or adjusted by turning the shaft q in order to give the collar s , by means of the cam or arm r , the desired position on the rod i with respect to the valve h .

10 The angular movement to be given to the shaft q and its arm r may be brought about by any suitable means, preferably with the agency of a screw-driver. To this end the projecting end of the shaft is provided 15 with a cut x as shown in Figure 3.

It will be seen that with the aid of the described means an exact adjustment of the valve spring m can be carried out from the outside of the casing without the necessity 20 of dismounting the constituent parts of the device.

The means for setting or adjusting the 25 thermostatic tube n is of a construction essentially similar to that hereinbefore described in connection with the spring m . The shaft v corresponding to the shaft q as regards both construction and mode of operation, carries on its inner end an arm z having a slot z' engaging with a pin z^2 of a 30 short sleeve z^3 rigidly connected with the respective end of the thermostatic tube n , whilst the other end thereof is firmly attached to the ring p bearing on the valve h .

The adjustment of the tube n may be 35 effected in the same manner as hereinbefore described with respect to the spring adjusting means shown in Figure 3.

From the foregoing description it will be 40 seen that simple and efficient means are herein provided for accomplishing the objects of my invention, but while the elements shown and described are well adapted to serve the purposes for which they are intended, it is to be understood, that the invention is not limited to the precise construction set forth, but include within its purview such changes as may be made within the scope of the appended claims.

What I claim, is:—

50 1. In a device of the character described, the combination with a casing, of a valve adapted to control the passage through said casing, a resilient member acting to yieldingly support said valve, a valve rod loosely carrying the valve, and a thermostatic member connected with said rod and mounted in the casing to act upon the valve in counteraction to the action of the said resilient member.

60 2. In a device of the character described, the combination with a casing, of a valve adapted to control the passage through said casing, a resilient member acting to yieldingly support said valve, a valve rod loosely carrying the valve, and a thermostatic mem-

ber adjustably connected with the said rod and disposed to counteract the said resilient member.

3. In a device of the character described, the combination with a casing, of a valve 70 adapted to control the passage therethrough, a resilient member acting to yieldingly support said valve, a valve rod loosely carrying the valve, a thermostatic member connected with said rod and acting on said valve in counteraction to the said resilient member, and means for setting and adjusting the two counteracting members in any desired position on the rod with regard to the valve 75 thereon.

4. In a device of the character described comprising a casing, a valve rod mounted in said casing having a valve therein, a thermostatic member mounted on one end to said valve rod and the other end to said valve, a spring on said valve rod for forcing said valve against the action of said thermostatic member, means including a link member for adjusting the thermostatic member, and means including an arm for adjusting the 80 tension of said spring.

5. In a device of the character described comprising a casing having a partition forming a valve seat, a valve rod secured in said casing and having a valve slidably mounted thereon, a thermostatic member mounted on one end on said valve rod and on the other end to said valve, a spring on said valve rod for forcing the valve into its valve seat against the action of said thermostatic member, means including a link for adjusting the thermostatic member on said valve rod, and means including an arm for adjusting the tension of said spring.

6. In a device of the character described 105 comprising a casing, a valve rod mounted in said casing and having a valve thereon, a thermostatic member mounted on one end on said valve rod and on the other end to said valve, a spring on said valve rod for 110 forcing the valve against the action of said thermostatic member, means including a link member for adjusting the thermostatic member, and means including an arm for adjusting the tension of said spring, the link 115 member and arm being connected to a shaft for effecting adjustment on the outside of the casing.

7. In a device of the character described 120 comprising a casing having a partition there- in forming a valve seat, a valve rod secured in said casing and having a valve slidably mounted thereon, a thermostatic member adapted to actuate said valve, a spring for forcing the valve against its valve seat, means including a link connected to a shaft for adjusting said thermostatic member, and means including an arm connected to a shaft for adjusting the tension of said 125 spring.

8. In a device of the character described comprising a casing having a partition therein forming a valve seat, a valve rod secured in said casing and having a valve slidably mounted thereon, a thermostatic member adapted to actuate said valve, a spring for forcing the valve against its valve seat, and means including a link connected to a shaft for adjusting said thermostatic member.
- 10 9. In a device of the character described

comprising a casing having a partition therein forming a valve seat, a valve rod secured in said casing and having a valve slidably mounted thereon, a thermostatic member adapted to actuate said valve, a spring for forcing the valve against its valve seat, and means including an arm connected to a shaft for adjusting the tension of said spring. 15

In testimony whereof I affix my signature.
HERMANN WARTENBERG.
